BACK BRUSH

James Moore, 78 Grove St., Ansonia, Conn.

Filed Aug. 1, 1962, Ser. No. 71,127

Term of patent 14 years

(Cl. D9—2)

FIG. 1 is a fragmentary rear elevational view of a back brush showing my new design;

FIG. 2 is a side elevational view thereof.

The handle portion is uniform in width throughout except as indicated in FIG. 2.

The dominant features of my design reside in the portions shown in full lines.

I claim:

The ornamental design for a back brush, as shown and described.
